(57) **CLAIM**

The ornamental design for vibration and temperature sensor with wireless communication function, as shown and described.

DESCRIPTION

1. Vibration and temperature sensor with wireless communication function

1.1 : Perspective

1.2 : Front

1.3 : Back

1.4 : Top

1.5 : Bottom

1.6 : Left

1.7 : Right

The parts shown by means of broken lines in the reproductions are not part of the claimed design; the product is a sensor attached to a bogie of a railcar and capable of measuring vibrations and temperatures and wirelessly transmit measurement results.
